PAGE PROJECTOR

August D. Eitzen, Rockville Centre, N. Y., assignor to News Projection Corporation, New York, N. Y., a corporation of New York

Application September 21, 1935, Serial No. 41,567

19 Claims. (Cl. 88—24)

This invention relates to page projectors.

Among the objects of the present invention, it is aimed to provide an improved projecting machine for association with a page printer including an improved compact optical system whereby the optical elements may be so arranged as to be housed in a very narrow cabinet not only to conserve space but also to enhance the appearance of the cabinet.

10 It is still another object of the present invention to provide an improved optical system for a projecting machine especially adapted for use with a page printer whereby the lamp may be disposed above the printer and thus the printer protected from the heat of the lamp and an extensive throw of image impressed light beam provided to effect the proper magnification with a given objective lens.

15 It is still another object of the present invention to provide an improved tape moving mechanism for effecting the movement of the tape across the light aperture including a continuously operating motor, a tape moving roller, a slip-page device and a control responsive to a deflection in the tape to effect the movement of a predetermined length of tape across the light aperture, such for instance as to correspond to the width of one or more line spaces according to the spacing of the printer.

20 It is still another object of the present invention to provide an improved combined projecting machine for news items and the like and an advertising machine including lamps and motor 25 for the projecting machine and advertising machine controlled by the printer associated with the projecting machine.

25 It is still another object of the present invention to provide an improved control operatively associated with the ticker whereby not only the electric circuit for the lamps of a projecting machine and an advertising machine but also for the motor of the same is established when the circuit of the ticker is established ready to receive a 30 message.

Among other objects of the present invention, it is aimed to provide an improved mount for the take-up reel.

35 These and other features, capabilities and advantages of the invention will appear from the subjoined detail description of one specific embodiment thereof illustrated in the accompanying drawings in which

Figure 1 is a perspective of a cabinet for a

machine made according to the present invention;

Fig. 2 is a transverse section on the line 2—2 of Fig. 1;

Fig. 3 is a diagram of the wiring used in the present invention for controlling the lamps and motor of the machine by the printer;

Fig. 4 is a fragmental perspective of the tape moving device;

Fig. 5 is a section on the line 5—5 of Fig. 4; and 10

Fig. 6 is a section on the line 6—6 of Fig. 4.

In the embodiment shown, there is provided a cabinet 1 having a base 2 mounted upon any suitable standards or supports, such as the casters 3, 3. Extending upwardly from the base 2, there are 15 provided the side walls 4, 5 and the front wall 6. Secured to the upper edges of the walls 4, 5 and 6, in the present instance, there is provided the top 7. The front wall 6 in the present instance has two openings formed therein, the lower one 20 preferably covered with a pane of glass 8 and the upper one with a translucent or rear projection screen 9 and an outer pane 9' of glass.

Above the base 2, there is provided in the present instance a horizontally extending platform 25 10 supported in place by the side walls 4 and 5. The rear of the cabinet 1 is closable by the removable wall 11 which is preferably provided with an opening 12 adjacent its lower end across which opening 12 there is formed a suitable foraminated screen 13 or the like. The wall 11 is also preferably provided with a second opening 14 in the present instance disposed above the middle of the wall 11 and provided with a foraminated screen 15. 30

The opening 14 in the present instance forms the upper outlet for the flue 16 for drawing off the hot air from the upper end of the lamp housing 17, the opening 12 in this instance forming an inlet for the fresh supply. 40

In the present instance secured to the inner face of the front wall 6 and extending down from a level above the upper end of the glass window 8 to a level below the lower end of the glass window 8 and in the present instance a short distance above the platform 10, there are provided the supporting plates 18, in the upper ends of which is journaled the shaft 19 for the sprocket wheels 20 and in the lower ends of which plates 18, there is journaled the shaft 21 for the sprocket 45 wheels 22. The shaft 19 is preferably disposed at a level above the upper end of the glass window 8 and the shaft 21 in the present instance well below the lower end of the glass window 8. 50

Furthermore, the sprocket wheels 20 are dis- 55

posed well to one side of the glass window 8, adjacent each end of the shaft 19 and the sprocket wheels 22 preferably disposed in alinement with the sprocket wheels 20 to receive the sprocket chains 23. The sprocket chains 23 are intended to support advertising material, such as car cards, to be brought into and out of display position adjacent the glass window 8 but other than the driving connection in association with the combination hereinafter to be described, this advertising device forms no part of the present invention.

The shaft 21 has fixed thereon the worm wheel 24 in mesh with the worm 25 on the shaft 26 having fixed on the inner end thereof the sheave 27 connected by the belt 28 with the sheave 29 on the shaft 30 of the motor 31 mounted on the platform 10, in the present instance, adjacent the printer or ticker 32 also mounted on the platform 10.

The invention here is directed mainly to a combination including a page printer and therefore the printer 32 will be assumed to be of the page printer type having a printing wheel 33 and tape discharging rollers 34 and 35 above the same for feeding the tape 36 upwardly out of the printer 32. The tape 36 in the present instance is fed upwardly from the supply reel 37 mounted to pivot at 38 on the brackets 39 extending upwardly from the base 2. In order to facilitate the upward feed of the tape from the reel 37, there is provided the resilient whisker 41 extending upwardly from the base 2 and engaging the tape 36 and yieldably drawing it away from the housing 40 as indicated in Fig. 2.

After leaving the whisker 41, the tape passes between the guides 42, passed the printing wheel 33 and then into engagement with the feed rollers 34 and 35 of the printer and from there upwardly in front of the lamp housing 17 to and over the rod 43 secured to the cheek plates 44 and 45 connected to the channel 46 extending across and supported by the side walls 4 and 5. From the rod 43, the tape passes down under the finger 47 secured to the ends of the levers 48 and 49 fixed to the shaft 50 journaled in the cheek plates 44 and 45. The finger 47 is also preferably provided with a resilient whisker 51 which engages the tape 36 on its way from the rod 43 to the finger 47 and deflects it inwardly away from the front wall 6 thereby to maintain the tape in contact with the finger 47 during the feeding impulse.

From the finger 47, the tape passes up over the rod 52 and then onto the cylinder 53 preferably composed of cardboard to produce the take-up reel 54. The cylinder 53 is mounted to rotate about the axis of the shaft 55 journaled in the cheek plate 44 and the auxiliary cheek plate 56 also secured to the channel iron 46. Fixed to the shaft 55, there is provided the large gear 57 in mesh with the small gear 58 fixed to the hub 59 of the escapement wheel 60 journaled on the shaft 61.

The escapement wheel 60 is preferably provided with a friction drive face 62 preferably engaged by the friction drive face 63 of the sheave 64 similarly journaled on the shaft 61. The sheave 64 is connected by the belt 65 with the sheave 66 fixed to the shaft 19.

In order to yieldably maintain the friction faces 63 and 62 in driving engagement with one another, there is provided the coil spring 67 tensed between the disc 68 on the shaft 61 and the collar 69 in engagement with the roller bearing

unit 70 mounted in the chambered portion 71 of the sheave 64.

Fixed to the outer end of the rocker shaft 50, there is provided the arm 72 to the lower end of which is pivotally connected the bar 73 having a slot 74 therein to receive the pin 75 extending from the cheek plate 44 and forming a guide for the bar 73. The rear end of the bar 73 is intended to cooperate with the teeth 76 of the escapement wheel 60. There are four such teeth 76 provided on the escapement wheel 60 in the present instance.

From the foregoing, it will thus appear that the rear end of the bar 73 will obstruct the path of movement of the teeth 76 to anchor the escapement wheel 60 against rotation with the sheave 64 when the bar 73 is in its forward position, that corresponding to the uppermost position of the finger 47 when the slack in the tape 36 has been taken up by the rewind reel 54 due to the driving connection between the sheave 64 and the escapement wheel 60.

It will furthermore appear that when the feed wheels 34 and 35 of the ticker 32 advance the tape a distance corresponding to one or more line spaces at a time that the slack, thereby formed in the tape between the rollers 34, 35 and the rod 43, will, due to the weight of the finger 47 and arms 48 and 49 enable the finger 47 to descend and take up such slack and thereby in turn rock the shaft 50 to rock the arm 72 and withdraw the bar 73 out of the path of movement of the teeth 76 to permit the friction drive between the sheave 64 and escapement wheel 60 to become effective in turn to actuate the gear 58 and thereby the rewind reel 54 until the slack has again been taken up, the finger 47 raised and thereby the bar 73 again projected into the path of movement of the teeth 76 to anchor the escapement wheel 60 against further rotation.

In order properly to center the cardboard cylinder 53 relative to the shaft 55, the shaft 55 is provided with a shouldered disc 77 having a concentric diminished portion 78 to fit the inner periphery of the cylinder 53 with the lateral edge 45 of the cylinder 53 abutting against the enlargement 79 of the shouldered disc 77. The enlargement 79 also has an inwardly protruding pin 79' to pierce the end of the cylinder 53 and thus facilitate a positive drive.

To engage the other end of the cylinder 53, there is provided a second shouldered disc 80 having a diminished portion 81 to engage the inner periphery of the cylinder 53 and the lateral outer edge of the cylinder 53 engaging the lateral face of the enlargement 82. The shouldered disc 80 is provided with a centrally located tapered opening 83 to receive the tapered end 84 of the pin 85 extending through the journal 86 in co-axial alinement with the shaft 55. The journal 86 in the present instance is mounted in the cheek plate 45.

In order to facilitate insertion and removal of the cylinder 53 from engagement with the shouldered discs 77 and 80, the pin 85 is removably mounted in the journal 86 and provided with an adjusting screw 88 screw-threadedly connected to the journal 86 with the locking point 87 to engage and anchor the pin 85 in proper position when the cylinder 53 is properly mounted.

The lamp housing 17 in the present instance consists of a removable wall 89, a front wall 90 and suitable side walls 91 provided with the bosses 92 to receive the rods 93 extending down from suitable brackets connected to the channel 75

46 and connected at their lower ends to the metal straps 94 extending rearwardly from the plates 18. In other words, the lamp housing 17 is slidably mounted on the rods 93 to facilitate access to the ticker and adjustment of parts and the like. The upper end of the lamp housing is preferably inclined with a front inclined top wall 95 spaced from the rear wall 89 to form an opening to communicate with the lower end of the flue 16 when the rear wall 11 is positioned as shown in Fig. 2.

5 The lamp housing 17 of course cannot be raised due to this flue 16 until the wall 11 has been removed. The lower end of the lamp housing 17 15 is preferably provided with an inclined wall 96 at its rear end provided with a spring 97 to press an angle mirror 98 into position against the inclined supports 99. Between the inclined wall 96 and the front wall 90, there is provided another inclined wall 100 to form a support for the condensing lens 101 adjacent the light aperture 102 across which the tape passes after leaving the rollers 34 and 35 on its way up to the rod 43. Forwardly of the light aperture 102, there is 20 formed an inclined wall 103 connected by the side walls 104 to the side walls 91 of the lamp housing 17 to form a support for the angle mirror 105, the lower end of the wall 103 being spaced from the front face of the wall 100 to permit the 25 passage of tape therebetween.

30 The lamp housing is also provided with suitable supports for the condensing lenses 106 and 107 between the angle mirror 98 and the lamp 108 secured in a horizontally extending socket 109. The lamp housing is also provided with a 35 suitable support for the spherical reflector 110 to direct the light rays from the lamp 108 through the condensing lenses 107 and 106 onto the angle mirror 98. The lamp housing is also provided 40 with two arms 111 extending from the wall 90 thereof to support the housing 112 of the objective lens unit so that the image impressed light beam after passing through the tape and being deflected upwardly by the mirror 105 will be received by the objective lens unit mounted in the housing 112 and directed upwardly onto the inclined mirror 113 suitably secured adjacent to the top 7 of the cabinet. The light rays are in turn deflected by the mirror 113 onto the inclined mirror 114 by it to be deflected onto the rear face 50 of the screen 9 so that the message may be read from the front face of the screen 9.

55 The housing 40 in the present instance preferably contains an automatic control, see disclosure in Patent No. 1,908,333, including an electromagnet 115, the conductor 116 of which is preferably operatively connected to the control relay of the printer 32, which electromagnet 115 is in turn connected by the conductor 118 to one terminal 60 of a switch 120 connected to the feed lines 121 and 122 respectively, the other terminal 123 of the switch 120 being connected by the conductor 124 to complete the return circuit.

65 The electromagnet 115 is in turn provided with an armature 125 pivotally connected to the conductor 126 connected to the conductor 118 and operable to engage the contact 127 of the conductor 128 which is connected to one terminal of the motor 31 by the conductor 129, to one terminal 70 of the lamp 108 by the conductor 130 and to one terminal of the lamp 131 of the advertising machine by the conductor 132.

75 The conductor 124 on the other hand is connected as an instance to the conductor 133 which in turn is connected to the other terminal of the

lamp 131 by the conductor 134, to the other terminal of the motor 31 by the conductors 135 and 136 and to the other terminal of the lamp 108 by the conductors 135 and 137.

8 The lamp 131 is shown in Fig. 3 as of the long 5 tubular type and preferably mounted behind the upper frame 138 above the glass window 8 and in the curved reflector 139, the lower end of which is open to permit the light rays from the lamp 131 indirectly to illuminate the advertising material carried by the chains 23.

10 It is obvious that various changes and modifications may be made to the details of construction without departing from the general spirit of the invention as set forth in the appended claims. 15

I claim:

1. The combination with a broad tape, of a page printer for marking said tape, a vertically extending projection field, and a tape moving device for drawing the tape upwardly through said projection field with the lines of printed matter extending transversely of the tape and horizontally, said tape moving device including a continuously operating motor, a drive operatively connected to said motor, a tape take-up roller, a slippage device for drivingly connecting said tape take-up roller with said drive, an escapement for anchoring said roller against rotation with said drive, and a control responsive to deflections in the tape when said printer advances the tape a 20 line space initially to draw the tape across said projection field and operatively connected to said escapement to actuate said escapement into and out of position to anchor said roller against rotation with said drive. 35

2. The combination with a broad tape, of a page printer for marking said tape, a vertically extending projection field and a tape moving device for drawing the tape upwardly through said projection field with the lines of printed matter extending transversely of the tape and horizontally, said tape moving device including a continuously operating motor, a drive operatively connected to said motor, a tape take-up roller, a slippage device for drivingly connecting said tape take-up roller with said drive, an escapement for anchoring said roller against rotation with said drive including an escapement wheel having a plurality of teeth spaced from one another, a bar 40 cooperating with said teeth to obstruct the path 45 of movement of the same and thereby anchor the escapement wheel against rotation, and an arm 50 operatively associated with said bar and in engagement with the tape to respond to deflections in the tape when said printer advances the tape 55 across said projection field and in turn to move said bar into or out of position to obstruct the rotation of said escapement wheel.

3. A tape moving device for drawing a tape 60 through a projection field including a continuously operating motor, a drive operatively connected to said motor, a tape take-up roller, a slippage device for drivingly connecting said tape take-up roller with said drive, an escapement for 65 anchoring said roller against rotation with said drive, and a control responsive to deflections in the tape, said control including two supports above the projection field across which the tape passes, a pivotally mounted arm resting on the 70 tape between said supports and drawing the tape upwardly across the projection field as it is supplied to the projection field and means operatively connecting said arm to said escapement 75 to actuate said escapement into and out of posi-

tion to anchor said roller out of rotation with said drive.

4. A tape moving device for drawing a tape through a projection field including a continuously operating motor, a drive operatively connected to said motor, a tape take-up roller, a slippage device for drivingly connecting said tape take-up roller with said drive, an escapement for anchoring said roller against rotation with said drive including an escapement wheel having a plurality of teeth spaced from one another, a bar cooperating with said teeth to enter the path of movement of said teeth in turn to obstruct the rotation of said escapement wheel, supports above the projection field across which the tape passes, an arm in engagement with the tape between said supports to respond to deflections in the tape, said arm by its own weight drawing the tape upwardly across the projection field, and means operatively connecting said arm with said bar in turn to actuate said bar into and out of position to obstruct the rotation of said escapement wheel.

5. The combination with a vertically moving tape, of a vertically extending projection field, a lamp, optical elements for directing a beam of light downwardly from said lamp and laterally through the tape at said projecting field, said lamp and optical elements being disposed to one side of said tape, a vertically extending rear projection screen, and optical elements for receiving the image impressed light beam leaving the tape and directing it upwardly and then laterally, thereupon above the path of movement of said tape and away from the screen and thereupon horizontally onto the rear face of said screen, said screen and latter optical elements being disposed to the other side of said tape.

6. The combination with a tape, of a vertically extending projection field, a lamp housing, a lamp in said housing having a horizontally extending socket, optical elements including a spherical mirror and a plurality of plano-convex spherical condensers for directing a beam of light downwardly from said lamp, an angle mirror for intercepting the downwardly directed beam of light and deflecting it laterally through a vertically extending tape at the projection field, an angle mirror beyond the tape for intercepting the image impressed light beam and directing it upwardly, a vertically extending rear projection screen, optical elements including two inclined mirrors and an objective lens unit for intercepting the image impressed light beam deflected upwardly by said second angle mirror and directing it first away from said screen and thereupon back onto the rear face of said rear projection screen, and a casing for said objective lens unit secured to, and disposed adjacent to, said lamp housing.

7. The combination with a marked tape, of a cut plano-convex spherical condenser having its plane face disposed in a vertical direction adjacent the path of movement of said marked tape, a lamp housing, a lamp in said housing, optical elements including a spherical convex mirror and a plurality of plano-convex spherical condensers for directing a beam of light downwardly from said lamp, an angle mirror for intercepting the downwardly extending beam of light and deflecting it laterally through said cut condenser and through the tape, a second angle mirror for intercepting the image impressed light beam passing through the tape and deflecting it upwardly alongside of said tape, a rear projection screen,

optical elements including a pair of inclined mirrors and an objective lens unit for intercepting the upwardly deflected image impressed light beam and directing it first away from said screen above the path of movement of said tape and thereupon back onto the rear face of said screen and a casing for said objective lens unit secured to, and disposed adjacent to, said lamp housing.

8. The combination with a support, of a broad tape, a page printer for marking said tape, a lamp housing vertically slidable on said support above said printer, said lamp housing including a lamp, optical elements for directing a beam of light rays from said lamp downwardly, guides for enabling the tape to move vertically upward without interfering with the vertical movement of said housing, a plano-convex condenser having its plane face disposed adjacent the path of movement of the tape delivered by said printer, and an angle mirror for intercepting the downwardly extending beam of light rays and deflecting it through said condenser and said tape to form an image impressed light beam.

9. The combination with a cabinet having a rear projection screen adjacent its upper end, of a broad tape, a page printer for marking said tape, vertically extending rods supported in said cabinet to extend upwardly from said printer, a lamp housing slidable on said rods to facilitate access to said printer, said lamp housing including a lamp, optical elements for directing a beam of light rays from said lamp downwardly, a plano-convex condenser having its plane face extending vertically, a tape moving device for moving the tape upwardly from said printer across the plane face of said condenser without interfering with the vertical movement of said housing, an angle mirror for intercepting the downwardly extending beam of light rays and deflecting it through said condenser and said tape to form an image impressed light beam, and other optical elements for intercepting the image impressed light beam so formed and deflecting it upwardly and then laterally onto the rear face of said projection screen.

10. The combination with a broad tape, of a page printer for marking said tape, a cabinet having a rear projection screen and a window, a projecting device, tape moving means for moving the tape as it is printed by said printer through the projection field of said projecting device, a lamp for said projecting device for forming images of the markings on the tape and directing them onto the rear face of said screen, a plurality of advertising displays, means for successively exhibiting said displays at said window, a lamp for illuminating said displays, a motor, means for operatively associating said motor with said tape moving means and with said exhibiting means, and a control including an electromagnet and an electric circuit including a switch, said lamps and said motor, said electromagnet being operatively associated with said printer to close said switch when the line circuit of said printer is closed in turn simultaneously to illuminate said lamps and initiate the action of said motor.

11. The combination with a cabinet having a removable wall and vertically extending supports adjacent to said wall, of a tape, a printer for marking said tape disposed in said cabinet, a lamp housing vertically slidable on said supports above said printer, a light aperture frame in said lamp housing, and guides for enabling the movement of said tape from said printer across said light aperture frame, said wall cooperating with

said lamp housing to anchor said housing against vertical movement when said wall is in closed position.

12. The combination with vertically extending supports, of a tape, a printer for marking said tape, a lamp housing vertically slidble on said supports above said printer, a light aperture frame in said lamp housing, and tape drawing means for drawing the tape upwardly across said light aperture without interfering with the vertical movement of said housing.

13. The combination with a tape, of a printer for marking said tape, a vertically extending projection field, a tape take-up device, a slippage device for drivingly connecting said take-up device with said motor, an escapement for anchoring said take-up device against rotation with said motor, and a control responsive to deflections in the tape when said printer advances the tape a line space to draw the tape across said projection field, said control including two supports above said projection field across which the tape passes, a pivotally mounted bracket resting on the tape between said supports and drawing the tape across the projection field as it is advanced by said printer, and means operatively connecting said arm to said escapement to actuate said escapement into and out of position to anchor said take-up device in or out of driving connection with said motor.

14. The combination with a tape, of a lamp housing having a lamp and a vertically extending projection field below the level of said lamp, a printer below said lamp housing, means for drawing the tape upwardly in a vertical direction across said projection field to one side of said lamp housing, optical elements for directing a beam of light downwardly from said lamp to the level of said projection field and then laterally through the tape at said projection field, a rear projection screen above the level of said lamp housing, and other optical elements for receiving the image impressed light beam leaving the tape and directing it upwardly along the other side of said tape and then above the path of movement of said tape and thereupon laterally onto the rear face of said screen.

15. The combination with a broad tape, of a page printer for marking said tape, a projection field, and a tape moving device for drawing the tape through said projection field with the lines of printed matter extending transversely of the tape and horizontally, said tape moving device including a continuously operating motor, a drive operatively connected to said motor, a tape take-up roller, a slippage device for drivingly connecting said tape take-up roller with said drive, an escapement for anchoring said roller against rotation with said drive, and a control responsive to deflections in the tape when said printer advances the tape a line space initially to draw the tape across said projection field and operatively connected to said escapement to actuate said escapement into and out of position to anchor said roller against rotation with said drive.

16. The combination of a tape, a lamp housing having a vertically extending projection field, a printer below said lamp housing, guides adjacent to and above said lamp housing, means for drawing said tape from said printer across said

guides upwardly and then back over said lamp housing, optical elements associated with said lamp housing for directing a beam of light downwardly along one side of said tape and then laterally through the tape at said projection field, a rear projection screen above and to one side of the path of movement of said tape, and other optical elements for receiving the image impressed light beam leaving the tape and directing it upwardly along the other side of said tape, then directly above said lamp housing and finally back onto the rear face of said screen.

17. The combination of a tape, a lamp housing having a vertically extending projection field, a tape take-up disposed above said lamp housing, a printer below said lamp housing, means also directly above said lamp housing cooperating with said take-up for drawing the tape from said printer upwardly and then back over said lamp housing, optical elements associated with said lamp housing for directing a beam of light downwardly along one side of the tape and then laterally through the tape at said projection field, a projection screen above and to one side of the path of movement of the tape, and other elements for receiving the image impressed light beam leaving the tape and directing it upwardly along the other side of the tape and then directly above said lamp housing and finally back onto the rear face of said screen.

18. The combination of a vertically extending tape, a source of light, a rear projection screen above the level of said source but to one side thereof, optical elements for directing a beam of light from said source downwardly, an angle mirror for receiving the beam of light so directed downwardly and directing it laterally through said tape, a second angle mirror for receiving the image impressed light beam leaving said tape and directing it upwardly, an angle mirror above the level of said source of light for receiving the image impressed beam of light thus directed upwardly and directing it downwardly and laterally back over said source of light, and an angle mirror directly above said source of light for receiving the beam of light so directed downwardly and laterally and in turn directing it laterally back across the path of the upwardly directed beam of light onto the rear face of said screen.

19. The combination of a vertically extending tape, a source of light, a rear projection screen above the level of said source but to one side thereof, optical elements for directing a beam of light from said source downwardly, an angle mirror for receiving the beam of light so directed downwardly and directing it laterally through said tape, a second angle mirror for receiving the image impressed light beam leaving said tape and directing it upwardly, a third angle mirror above the level of said source of light, an objective lens unit positioned at the focal point of the light beam directed upwardly to invert the image impressed light beam and direct it onto said third angle mirror, and a fourth angle mirror directly above said source of light for receiving the imaged impressed light beam reflected by said third angle mirror and in turn directing it laterally back across the path of the upwardly directed beam of light onto the rear face of said screen.
